UNITED STATES PATENT OFFICE.

MARCEL ANDRÉ JULLIEN AND EMILE LOUIS DESSOLLE, OF LEVALLOIS-PERRET, FRANCE.

LITHOGRAPHIC PRINTING.

No. 877,483.

Specification of Letters Patent.

Patented Jan. 21, 1908.

Application filed November 15, 1905. Serial No. 287,549.

To all whom it may concern:

Be it known that we, MARCEL ANDRÉ JULIEN and EMILE LOUIS DESSOLLE, two citizens of the Republic of France, residing at 5 Levallois-Perret, in France, have invented new and useful Improvements in or Relating to Lithographic Printing, of which the following is a specification.

This invention relates to an improved 10 lithographic printing surface and the method of treating the same and consists of a dull metal plate intended to replace the ordinary lithographic stone in printing, and is specially adapted to that purpose, owing to its 15 electrolytic structure, seen from the metallurgical point of view.

The invention relates, moreover, to the method of using the said plates.

This use of the special form of metal 20 sheets, or plates makes it possible to do away with the ordinary lithographic stones which are heavy, cumbersome, expensive and fragile, and also to make use of rotary presses for printing. It also does away with 25 the use of sheets or plates of zinc, aluminium or other rolled metals, which have already been tried, and the use of which had to be limited to a very large extent owing to the difficulty of drawing on their surfaces, and 30 also owing to their quick oxidation, which by affecting their sharpness, considerably reduces the number of copies that can be taken, and makes it impossible to keep them for subsequent printing.

According to this invention thin sheets of 35 suitable thickness and size are used, made of one metal or of several superposed metals, obtained in an electrolytic way, or sheets of metal obtained by ordinary metallurgical 40 processes, on which the same, or other, metal is electrolytically deposited, this deposit being specially made for the purpose of obtaining a sufficiently thick, dull and grained surface, on which drawing can be executed perfectly well and which are suitable for lithographic transfer.

In order to prevent work executed on the 50 surfaces of these sheets from undergoing any modification of the kind which takes place on the surfaces now used, other than stone, these surfaces are constituted by a precious metal, such as silver, gold, etc.

When it is desired to use such a plate or sheet on a rotary press, the sheet is rolled 55 on, and fixed to the cylinder by means of a device similar to those now used.

Experience has proved that by means of such sheets covered with an electrolytic deposit of precious metal, prints equal to or better than those made from stone can be 60 obtained.

In order to execute a transfer on the electrolytically prepared metal sheet, it is necessary, as for stone, to prepare the surface by means of solutions giving a suitable chemical reaction, so as to enable a large number 65 of copies to be printed.

The operations take place in the following manner:

1. The sheet is carefully cleaned with pure 70 alcohol.

2. The drawing is transferred in the same manner as to stone.

3. The whole is then washed with a very weak solution of nitric acid having mixed 75 therewith powdered carbonate of lime, to clean up the transfer and prepare it for the application of gum. The presence of lime carbonate in the weak nitric acid produces the evolution of carbon di-oxid which causes 80 local movements or currents of the weak acid and increases the efficiency of the action of the said acid. After the transfer has been treated with the acid for about two minutes it is washed with water to remove all traces 85 of acid and dirt, after which it is gummed strongly and dried.

4. The sheet is then inked with stiff color by means of a hand roller, in the same manner as a stone. 90

Subsequently a little talc and powdered resin can be added, adding a little American potash to the water for washing, and finally the whole is strongly gummed.

As soon as the work is dried, the transfer 95 is ready to be secured to the printing machine, and prints of great fineness without any blurred or exaggerated portions can be obtained in large numbers.

After the printing, the transfer can be kept 100 for subsequent printing at a distant date, as the metallic surface used is inoxidizable.

If it is desired, on the contrary, to use the sheet for a new transfer, it is easy to remove the first transfer without scraping, using 105 pumice stone or the expensive graining which is necessary in the case of the stones and metals at present employed.

The procedure is as follows:—1. Remove the ink by means of turpentine essence. 2. 110 Wash carefully. 3. Rub out the transfer by means of a concentrated solution of Ameri-

can potash applied to a pad with a little rotten stone in order not to damage the surface, until the picture has completely disappeared, and then wash carefully. 4. Wash with a 5 solution of diluted sulfuric acid, and finally, if necessary, with a very weak solution of bi-chromate of potash. The plate is then ready for a new transfer.

It is obvious that instead of the solutions 10 indicated, any other solutions, alternately basic and acid, can be used which are adapted to fulfil the same object.

Having thus described the nature of our invention and the means for carrying out the 15 same, we declare that what we claim is:

A method of producing a lithographic printing plate which consists in subjecting a metal plate having an electrolytically de-

posited surface of precious metal of granulated structure to a cleaning agent such as 20 alcohol, applying a transfer to the cleaned surface, washing said surface with a mineral acid containing a solid adapted to combine therewith with the evolution of carbon dioxide gas, and finally preparing said surface 25 for printing in the manner practiced in the case of a lithographic stone, substantially as described.

In testimony whereof we have affixed our names to this specification in the presence of 30 two subscribing witnesses.
